[57] CLAIM

The ornamental design of a container spout, as shown
and described.

DESCRIPTION

FIG. 1 is a top left perspective view of a container spout
showing a first embodiment of my new design, and
showing the spout in a closed position;

FIG. 2 is a perspective view, taken from the top right
thereof showing the spout in the open position;

FIG. 3 is a right side elevational view thereof, the left
side being a mirror image;

FIG. 4 is a front elevational view thereof;

FIG. 5 is a rear elevational view thereof; and,

FIG. 6 is a bottom view thereof.

FIG. 1

FIG. 2

FIG. 3
